PULLING DEVICE

Peer D. Nielsen, Lorain, Ohio, assignor to National Tube Company, a corporation of New Jersey

Application May 17, 1939, Serial No. 274,271

1 Claim. (Cl. 104—173)

This invention relates to pulling devices, but it is particularly concerned with an arrangement for hauling cars back and forth over tracks located in the path of falling materials.

The accompanying drawing illustrates a specific example of the invention installed under the limestone and ore storage bins of an open hearth steel plant, for the purpose of pulling the cars over the trackway carrying the cars which are 10 gravitationally loaded from the bins and which carry the materials to the open hearths.

In the drawing:

Figure 1 is a plan;

Figure 2 is an elevation;

15 Figure 3 is an enlarged section of a feature of the invention; and

Figures 4 and 5 are sections showing other features.

More specifically, the drawing illustrates the 20 narrow gauge trackway 1 running between the columns 2 supporting the ore and lime bins overhead, these bins being provided with the usual valved chutes through which the materials may be dropped into the cars running on this trackway.

According to the prior art, the cars are hauled or pulled over the trackway 1 by wire ropes resting on the floor to one side of the trackway or in an open topped conduit on the center line of the 30 trackway, the cars being provided with suitable means for connecting them to the ropes in either instance. In the first instance, the workmen are in constant danger of being injured, while in the second instance the materials discharged from 35 the bins, and which accidentally spill to the floor, clog the open topped conduit so as to cause trouble. One object of the present invention is to provide a pulling device which will obviate these difficulties.

According to the present invention, the rope 3 is guided by a suitable system of sheaves fixed to the columns 2 on one side of the trackway 1, to form a vertical loop with the top portion of the loop sufficiently high to be beyond the reach of 45 the workmen and with the bottom portion of the loop running through a guideway 4 located near the floor level. A suitable overhead powering system 3^a serves to reversingly power the rope 3.

This guideway 4 consists of an appropriate 50 number of lengths of commercially obtainable pipe arranged in abutting relation and butt welded together as at 4^a, the joints being made so as to provide a smooth, continuous inside. The pipe used for this purpose should be of suitable diameter and have a relatively thick wall, while

the various butt welded sections may be mounted in any convenient fashion.

Each of the pipe sections is cut to provide it with a longitudinally extending slot 5, the slot of each section being in alignment with the slot of each other section, whereby to provide a tubular guideway having a longitudinally extending slot opening into its inside. The pipe sections are so mounted that this slot opens horizontally, the result being the provision of a guideway having a 10 rounded exterior leading downwardly to the horizontal slot so as to deflect material falling from the bins away from the slot. At the same time the workmen are protected from contacting the rope traveling inside the guideway.

A shuttle 6 rides inside the guideway, the wire 15 rope having opposite ends connecting with bars 7 reciprocating in opposite ends of the shuttle 6 and restrained from such reciprocation by compression coil springs 8. Movement of the 20 rope 3, therefore, causes movement of the shuttle 6 inside the guide 4.

This shuttle is provided with an angularly extending arm 9 which is flat and projects through the slot 5 in the guideway, this arm being adapted 25 for connection with the cars on the trackway 1 by way of a suitable linkage such as a short length of rope. When such connection is made, the shuttle 6 serves to pull the linked car over the trackway 1 and, since the guideway 4 is to one 30 side of the trackway 1, this places a thrust on the shuttle. To accommodate such thrust, the shuttle is provided with rings 10 suitably spaced and fixed to the outside of the shuttle so as to bear 35 against the inside of the guideway, these rings providing guides transmitting the mentioned thrust to the guideway. It is for this reason that the guideway must have a relatively thick wall, since this wall must serve to transmit the thrust stress to the bin columns 2.

40 Since the shuttle reverses, the arm 9 is pivotally fixed to the shuttle by a pin 11 and works through a slot 12 formed in the shuttle body, this slot being of restricted length so as to restrict the swinging of the arm 9 to prevent its disappearing within the guideway. This arrangement, incidentally, maintains the arm 9 in its angular position respecting the shuttle, during the hauling 45 of a car.

I claim:

50 An arrangement for hauling cars back and forth over tracks located in the path of falling materials, characterized by the use of a hollow guideway extending longitudinally alongside the tracks and having a longitudinal slot opening 55

horizontally into its inside, a rope reciprocative in said guideway and a shuttle inside said guideway and fixed to said rope, said shuttle having an arm angularly extending through said slot for connection to the cars and said guideway taking the thrust imparted said shuttle by transmission of pull through its angularly extending arm, said guideway having a rounded exterior leading down to said slot for deflecting falling materials from

said slot, said shuttle having at least one coil spring through which said rope is fixed to said shuttle and which is entirely inside said guideway so as to be protected from said falling materials, and said shuttle being provided with at least one ring having an outside shape and size causing it to closely fit and ride the inside of said guideway so as to keep said inside clean. 5

PEER D. NIELSEN.
